UNITED STATES PATENT OFFICE.

WILLIAM PEARL, OF CHICAGO, ILLINOIS.

DESIGN FOR A SEAT-POST FOR CYCLES.

SPECIFICATION forming part of Design No. 31,689, dated October 17, 1899.

Application filed September 14, 1899. Serial No. 730,524. Term of patent 3½ years.

To all whom it may concern:

Be it known that I, WILLIAM PEARL, a citizen of the United States, residing in the city of Chicago, county of Cook, and State of Illinois, have invented and produced a new and original Design for Seat-Posts for Cycles, of which the following is a specification, reference being had to the accompanying drawings, forming part thereof.

10 Figure 1 is a view of a seat-post, showing my design when seen from a point to the rear and slightly above said seat-post. Fig. 2 is a perspective view of the seat-post, taken from a point located obliquely beneath and at the 15 side thereof. The rear lug appears slightly foreshortened.

As shown in the drawings, the leading or 20 material feature of my design consists of the long and slender neck A of the rear lug B and the gradually-diverging branches C C, forming the fork at the lower portion of said lug. The cross-section of said neck A at the most 25 contracted portion D thereof is approximately circular, and the greatest length of said rear lug B, exclusive of the insets or stocks E E at the lower extremities thereof, more or less closely approximates a length equal to four diameters of said portion D. When viewed

from the side, the upper and lower outlines of said rear lug B are substantially parallel, 30 but converge slightly as they approach the said insets or stocks E E. When viewed from a point to the rear and slightly above, as in Fig. 1, the lateral outlines of said rear lug B present sweeping and graceful curves symmetrically placed with reference to a line extending longitudinally through the center of said lug. Said lateral outlines diverge from said contracted portion D to meet the lateral outlines of the sleeve F of said seat-post and 40 also diverge from said portion D as they approach the lower extremities of said lug; but the curvature of said lateral outlines decreases as the said lower extremities are approached, and before said lower extremities 45 are reached said lateral outlines become substantially rectilinear.

Having described my invention, what I claim as new, and desire to secure by Letters Patent, is—

The design for a seat-post for cycles, as herein shown and described.

WILLIAM PEARL.
